2,378,347

NOISELESS VACUUM CLEANER

Lee Barton Williams, Pittsburgh, Pa.

Application February 10, 1944, Serial No. 521,858

1 Claim. (Cl. 15—16)

This invention relates to vacuum cleaners, the primary object of the invention being to provide a vacuum cleaner wherein the suction is created by the action of bellows, which results in the carpet or rug under treatment, being alternately 5 and suddenly drawn into engagement with the nozzle of the device and released, to the end that a beating action takes place at the nozzle of the machine, liberating foreign matter from the carpet or rug, the foreign matter being drawn into the 10 machine by the suction created within the bellows.

Another important object of the invention is to provide a vacuum cleaner which will be practically noiseless in operation, owing to the elimination of the noisy high-speed suction fan, commonly used in vacuum cleaner construction.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

Referring to the drawings

Figure 1 is a side elevational view of a vacuum cleaner, constructed in accordance with the invention.

Figure 2 is a plan view thereof.

Figure 3 is a sectional view taken on line 3—3 of Fig. 1.

Figure 4 is a sectional view taken on line 4—4 of Fig. 2.

Referring to the drawings in detail, the frame of the vacuum cleaner is indicated generally by the reference character 5 and embodies a nozzle section 6 which is of tubular construction, transversely disposed tubular sections 7 and 8 and a discharge section 9. The nozzle section 6 communicates with the tubular section 7, at a point intermediate its ends, and the discharge section 9 communicates with the tubular section 8, at the center thereof.

The ends of the tubular sections 7 and 8 are open, and are fitted against openings of the bellows 10 that have their inner walls 11, bolted to the flanges 12 by means of the bolts 13. Openings 14 are formed in the inner walls 11 of the bellows, so that air may pass into the bellows, during the suction action of the bellows. Inwardly closing flap valves 15 normally close the ends of the tubular section 7, and operate to admit air and foreign matter drawn into the

machine, to the bellows, on the suction operation of the bellows.

Openings 16 are formed in the inner walls 11 of the bellows, and these openings are disposed opposite to the ends of the tubular section 8, establishing communication between the bellows and tubular section 8. These openings are closed by means of the flap valves 17 that open inwardly, under the suction stroke of the device, and close as the bellows expand. As the flap valves 17 open, it will be seen that air and foreign matter contained in the air, will be forced through the discharge section 9, where the foreign matter will be deposited in the bag 18 which is shown 15 as connected with the discharge section 9.

Mounted on the frame of the machine, and disposed adjacent to the upper end of the nozzle section 6, is a motor 19, the motor being braced by the bracket 20, in which it is held.

The reference character 21 designates a pulley which is secured to the lower end of the motor shaft, the pulley having a V-shaped groove, to receive the correspondingly shaped belt 22, which belt also operates in the V-shaped groove of the substantially large pulley 23 which is mounted on a shaft that extends from the upper surface of the frame of the machine. Eccentrically connected with the substantially large pulley 23, is the connecting link 24, which has pivotal connection with the arms 25, at their inner ends, the outer ends of the arms 25 being pivotally connected with the outer or movable sides 26 of the bellows, through the brackets 27. Thus it will be seen that due to this construction, rotary movement of the pulley 23, will operate the arms to cause the arms to take the positions shown by Fig. 3 of the drawings, whereupon the bellows will be collapsed. Upon further rotation of the pulley 23, the arms will again be extended, moving the bellows to the positions shown by Fig. 2, which constitutes the suction stroke of the bellows to draw air and foreign matter, into the machine. It will of course be understood that on the suction strokes of the bellows, the flap valves 14 will open, admitting the air to the bellows, and that upon collapsing of the bellows, the flap valves 17 will open while the valves 14 are closed. The only exit for the air in the bellows, will be through the valves 17, to the end that the air and foreign matter will be forced through the discharge section 9 and deposited in the bag 18.

The outer or movable wall of each bellows, is formed with an elongated opening that is normally closed by means of the hinged closure 28, which

affords means whereby ready access may be had to the interior of the bellows for repair or cleaning purposes.

The handle of the machine is indicated by the reference character 29 and may be of any convenient construction to facilitate the operation of the vacuum cleaner.

From the foregoing it will be seen that due to the construction shown and described, I have provided a vacuum cleaner wherein the suction through the machine is created by means of bellows, mounted at opposite sides thereof, the bellows operating silently, providing a vacuum cleaner which is noiseless.

It might be further stated, that the suction created by the bellows, will cause the rug or carpet over which the vacuum cleaner is being moved, to be suddenly drawn into engagement with the nozzle of the machine, and then released, providing the same result as a beater, commonly used in vacuum cleaner structure, for releasing the dirt or foreign matter, to be picked up during the suction strokes of the bellows.

What is claimed is:

A vacuum cleaner comprising a frame, including a nozzle, spaced transversely disposed upper and lower tubular sections, forming a part of the frame, said lower tubular section communicating with the nozzle, outwardly opening flap valves normally closing the ends of the lower tubular section, inwardly opening flap valves normally closing the ends of the upper tubular section, a discharge pipe communicating with the upper tubular section, bellows extending throughout the lengths of the sides of the frame and adapted to communicate with the transversely disposed sections through the ends thereof, arms connected with the bellows, a power device embodying a large pulley, a connecting link eccentrically connected with said pulley, said connecting link being pivotally connected with the adjacent ends of the arms whereby movement of said pulley acts to operate the arms and bellows, drawing air through the machine, and means for rotating the pulley.

LEE BARTON WILLIAMS.
